CLAIM

The ornamental design for a floodlight controller with camera, as shown and described.

DESCRIPTION

FIG. 1 is a front perspective view of a floodlight controller with camera according to the present design; FIG. 2 is a front elevational view of the floodlight controller with camera of FIG. 1; FIG. 3 is a rear elevational view of the floodlight controller with camera of FIG. 1; FIG. 4 is a right-side elevational view of the floodlight controller with camera of FIG. 1; FIG. 5 is a left-side elevational view of the floodlight controller with camera of FIG. 1; FIG. 6 is a top plan view of the floodlight controller with camera of FIG. 1; and, FIG. 7 is a bottom plan view of the floodlight controller with camera of FIG. 1. In the drawings, the broken lines depict portions of the floodlight controller with camera that form no part of the claimed design.
